UNITED STATES PATENT OFFICE.

JOHN M. SCHORB, JR., OF PLAINFIELD, N. J., ASSIGNOR TO CARRIE L. SCHORB, OF SAME PLACE, AND JOHN I. HOLLY, OF NEW YORK, N. Y.

CAP FOR CARRIAGE-AXLES.

SPECIFICATION forming part of Letters Patent No. 327,727, dated October 6, 1885.

Application filed December 19, 1884. Serial No. 150,715. (No model.)

To all whom it may concern:

Be it known that I, JOHN M. SCHORB, Jr., of Plainfield, in the county of Union and State of New Jersey, have invented a new and 5 useful Improvement in Caps for Carriage-Axles; and the following is declared to be a description of the same.

My present invention is designed as an improvement upon the device secured to me by 10 Letters Patent No. 302,038, dated July 15, 1884.

My invention relates to an improvement in 15 caps for securing carriage and other wheels upon their axles, said cap being constructed with a spring push-pin and lever operating a locking-pin, said locking-pin passing through the cap and into a hole in the axle. The cap is tubular to pass upon the end of the axle, and there is a washer between the cap and 20 the end of the hub.

The foregoing devices are set forth in my aforesaid patent, the essential and most important part of my present invention being the combination, with the said parts, of a ring 25 or band of metal surrounding the cap, to which band or ring a partial rotation can be imparted to either secure the locking-pin and lever so that they cannot be accidentally operated or to release the same when it is desired 30 to remove the cap. A slot in this ring and a pin in the cap limit the movement of the ring.

In the drawings, Figure 1 is a longitudinal section of part of a wheel hub and axle and 35 of the cap. Fig. 2 is a cross-section of the same at the line *x x*. Figs. 3 and 4 are plan views of the securing-cap, with the surrounding ring or band of modified forms. Fig. 5 is a section at the line *y y* of Fig. 3, and Fig. 6 40 is a section at the line *z z* of Fig. 4.

The wheel and hub *a*, axle *b*, and protecting-ring *c* are of any usual construction.

The cap *d* is circular in form, and has a recessed flange, 1, for a washer, 3, and it is 45 tubular, so as to pass upon the axle *b*. There may also be a peripheral rib or flange, 2. The cap *d* is slotted for the reception of the lever *e*, and perforated for the locking-pin *f* and pin *g* and its spring *g'*. The locking-pin 50 *f* is slotted for the reception of the forked end

of the lever *e*, and has a pin, 4, across it and in the fork of said lever *e*. The lever *e* is secured in its slot in the cap by the pin 5, which forms the pivot, and the pin *g* is slotted for the other end of lever *e*, and this end of the 55 lever *e* is made with a button or knob, *h*, over the pin *g*, and upon which the finger is placed in operating the parts.

When the knob *h* is pressed upon, the spring-pin *g* is depressed, and the lever *e* 60 raises the locking-pin *f*, as in my former patent. When this has been done the cap can be either placed upon or removed from the end of the axle.

The ring or band *k* is designed to lock the 65 parts and prevent the accidental withdrawal of the pin *f* and the separation of the cap from the axle. The ring or band *k* in Figs. 1 and 2 surrounds the cap between the flange and rib 2. There is a slot at *i* in this ring, and a 70 pin, *i'*, in the cap, to limit the partial rotary movement that can be given to the ring *k*. The position of the slot in band *k* and the pin in the cap is immaterial. The ring *k* is notched at *l*, and said notch is of such shape 75 (see Fig. 4) that when the ring is turned and the notch brought to the pin *g* the lever *e* and locking-pin *f* can be operated to move such pin and remove or replace the cap. The ring or band *k* in Figs. 3 and 5 is shown as 80 narrow, to cover the locking-pin *f*, the ring being retained in place by the pin *i'* in the cap, that also limits its partial rotary movement.

The cap shown in Figs. 4 and 6 is made without the rib 2; but otherwise it and the 85 ring *k* are the same as Figs. 1 and 2.

A partial revolution is all that is necessary to impart to ring *k*, and the slot at *i* is made accordingly of a length to properly limit the turning motion.

I claim as my invention—

1. The combination, with the carriage axle and cap, of a pivoted lever, *e*, having a button, *h*, at one end and a fork at the other end, the locking-pin *f*, connected to the fork, the 95 spiral spring *g'*, and pin *g* within a hole in the cap, and acting against the lever beneath the button-head, substantially as specified.

2. The combination, with the carriage axle and cap, of a locking-bolt passing through 100

the cap into a recess in the axle, and a ring or band surrounding the cap and capable of being turned to retain the bolt in its place, substantially as specified.

5 3. In a cap for carriage-axles, the combination, with the locking-pin *f*, the lever *e*, and pin *g*, of a ring or band, *k*, slotted at *i* and *l*, and the pin *i'*, for limiting the movement of

10 said band *k*, substantially as and for the purposes set forth.

Signed by me this 15th day of December, A. D. 1884.

JOHN M. SCHORB, JR.
